[57] ABSTRACT

A curling broom which comprises a handle, a paddle attached to the handle, which paddle is made of synthetic material, and a fabric cover enclosing the paddle. The paddle is tubular in form and made of flexible plastic. The thin wall provides desirable "spring-back" and yet the tube design ensures sufficient rigidity. The walls are downwardly tapered in thickness to provide gradually changing flexibility. A slab of foam plastic is inserted within the tube for altering the weight and flexibility within narrow limits.

CURLING BROOM

BACKGROUND OF THE INVENTION

This invention relates to a broom for use in the game of curling. More particularly, it is concerned with a broom having a covered flexible paddle made of synthetic material. The broom is designed to simulate the feel and sweeping action of a conventional corn straw curling broom.

In my Canadian patent number 820557, I describe a curling broom having a solid rubber paddle with a fitted pile cover; the paddle is attached to the lower end of the broom handle. The thickness and durometer hardness of the rubber are selected to provide a paddle having flexibility and spring-back characteristics similar to the straws of a conventional curling broom. However, the rubber paddle has a shortcoming in that it is heavy; users tend to become tired when sweeping energetically with it. I have therefore worked toward developing a paddle which is lighter than the rubber version, and yet which has a sweeping action similar to that of the corn straw broom.

SUMMARY OF THE INVENTION

It is an object of this invention to provide a broom having a synthetic paddle characterised by weight, flexibility, spring-back and bending properties similar to the straws of a conventional curling broom.

It is another object to provide a broom paddle which bends in a smooth curve when pressed against the ice.

It is another object to provide the broom with means for altering the weight distribution, flexibility, and bending characteristics of the paddle.

It is another object to provide a curling broom which is long-lasting and economical to make.

In accordance with the invention, a plastic paddle having a flexible tubular lower end is provided. The walls of the tube are downwardly tapered, whereby only the bottom few inches can be easily flexed. When the paddle is pressed against the ice, the tapered construction ensures that it bends gradually from the bottom in the form of a curve, rather than creasing intermediate its ends. The paddle is light in weight, due to its hollow structure. When the thin walls of the tube are bent, they have the property of quickly springing back to the vertical plane when released — this is important in achieving the desired sweeping "action". A flexible filling element, such as a slab of foam plastic, can be positioned within the tube cavity. The location and thickness of the filling element can be changed to alter the weight distribution, and flexibility and bending characteristics of the tubular end.

DESCRIPTION OF THE DRAWING

The invention is illustrated in the accompanying drawings in which:

FIG. 1 is a partially sectional side view of the broom;

FIG. 2 is a front view, partly in section, of the broom;

FIG. 3 is a cross-section of the upper end of the paddle taken along the line 5—5 in FIG. 2;

FIG. 4 is a perspective view of the upper end of the cover, showing its fastening;

FIG. 5 is a sectional side view of the paddle with certain dimensions identified by letters;

FIG. 6 is a sectional front view of the paddle with certain dimensions identified by letters.

DESCRIPTION OF THE PREFERRED EMBODIMENT

With reference to the drawing, a curling broom 1 is shown. The broom 1 comprises a handle 2, a plastic paddle 3 attached to the lower end of the handle, a filling member 4 positioned within the tubular portion 5 of the paddle, and a cover 6 fitted over the paddle.

The paddle 3 comprises a rigid upper portion 7 integrally joined with the tubular lower portion 5. The upper portion 7 is formed with a thick, upwardly tapered sidewall 8 which defines a socket 9. The socket 9 is adapted to receive the handle 2. Screws 10 connect the handle 2 and socket portion 7 together. The tubular lower portion 5 has downwardly tapered side walls 5a and end walls 5b. The thickness and taper of the walls 5a, 5b are selected so that the bottom two or three inches thereof are readily flexed and there is a gradual increase in the rigidity of the lower portion 5 from that point up to its junction with the upper portion 7. It will be noted that the end walls 5b are somewhat thinner than the side walls 5a to permit some twisting of the tubular portion 5 during sweeping.

The dimensions of the paddle 3 vary, depending on the particular plastic used. I find that ethylene vinyl acetate copolymer resin provides desirable flexibility and toughness, even at sub-zero temperatures. This material is available from DuPont of Canada Limited under the trade mark Alathon E/VA 3180 and is characterised by the following properties:

Table I

% vinyl acetate — 28
Melt index — 15.0
Stiffness, psi — 1,700
Vicat softening point °F — 125
Ultimate tensile strength, psi — 1,500
% elongation — 900

Using this material, I make a paddle having the following dimensions:

Table II

$a = 12''$	$d = 1''$
$b = 6''$	$e = 2''$
$c = 1 \frac{1}{4}''$	$= 4 \frac{1}{2}''$

The thickness of the wall 5b, as shown in FIGS. 2 and 6, decreases from three-eighth inch to one-sixteenth inch, and the thickness of the wall 5a, as shown in FIGS. 1 and 5, decreases from one-eighth inch to one-sixteenth inch. A filling member 4 is positioned within the cavity 11 of the tubular lower portion 5. A one-half inch $\times$ 2 inch $\times$ 4 inch $\times$ 14 inches slab of plastic foam is satisfactory for use in the paddle whose dimensions are listed in Table II. The slab 4 is sufficiently thick to press against the interior surfaces of the side walls 5a; as a result, friction forces act to hold the slab in place. However, the slab can be easily shifted to a new position along the length of the lower portion 5. In use, the slab offsets buckling or creasing of the lower portion 5 and aids it to bend in the form of a smooth curve. When it is shifted longitudinally, the weight distribution and rigidity of the tube is altered within modest limits to satisfy the user's preferences.

A water-proof, non-stretch, non-shrink durable cover 6 is fitted over the paddle 3. The cover 6 is held in place by tightening a multiple hook-type fastener 14 around the upper portion 7. One suitable material for the cover

is a 5/16 inch thick nylon pile attached to a plastic-coated nylon backing.

A paddle made in accordance with the invention provides a combination of weight, spring-back, flexibility and bending properties which is similar to that of the bunch of straws of a conventional corn straw curling broom; the "feel and sweeping action" of the synthetic paddle approximates that of the straw broom.

What is claimed is:

1. A curling broom for sweeping ice which comprises:
a handle;
a plastic paddle attached to the handle, said paddle having a substantially rigid upper portion, defining means for connection with the handle, and a flexible, tubular lower portion joined to the upper por- 10
15

tion, said lower portion having downwardly tapered walls;

a flexible filling member positioned within the cavity of the tubular lower portion and cooperating with the lower portion's walls to remain stationary within the cavity, said member being adapted to be shifted to a new position along the length of the tubular lower portion when desired whereby the weight distribution, flexibility and bending properties of the lower portion are altered; and
a cover fitted over the paddle to provide an ice-wiping surface.

2. The broom as set forth in claim 1 wherein:
the filling member comprises a slab of foam plastic.
